T. WILSON

ROLLING MILL APPLIANCE

Filed Aug. 13. 1921

UNITED STATES PATENT OFFICE.

TOM WILSON, OF JOHNSTOWN, PENNSYLVANIA.

ROLLING-MILL APPLIANCE.

Application filed August 18, 1921. Serial No. 491,036.

To all whom it may concern:

Be it known that I, Tom Wilson, a citizen of the United States, and a resident of the city of Johnstown, county of Cambria, and State of Pennsylvania, have invented certain new and useful Improvements in Rolling-Mill Appliances; and I do hereby declare the following to be a full, clear, and exact description of the invention, such as will enable others skilled in the art to which it appertains to make and use the same.

My invention relates to a rolling mill appliance or apparatus which is adapted to handle blooms and billets which are approximately square in section, with or without rounded corners, or slabs which are approximately rectangular with either square or rounded corners, and my apparatus is adapted to deliver the same to the rolls or receive the same from the rolls and turn the pieces on their longitudinal axes as may be desired for rolling, reduction or shaping in the different grooves of the mill rolls.

My invention is particularly applicable to what is known as a two-high mill, which is provided with a pair of reversing rolls provided with approximately rectangular grooves therein and collars forming part of the side boundaries of said grooves, the rolls being adapted to be moved apart or together to adjust the sizes of the different passes in the rolls.

In connection with the rolls is a pair of tables, one on each side of the mill, which are provided with a plurality of rollers adapted to be rotated in either direction or to be held stationary as desired, and these rollers are provided with collars or projections thereon and so spaced apart as to accommodate the various sizes which are rolled. In connection with the tables I also provide a manipulator with an operating portion, which has a series of serrations or notches formed in the metal bars thereof, which are adapted to be moved upwardly or downwardly preferably by a partial rotation around a pivot considerably removed from the body of the manipulator, which therefore moves in an arc somewhat approaching a straight line. My manipulator may also be moved in a straight line manner if desired.

After the blooms, billets or slabs issue from the rolls and they are on the table rollers they are lifted by the manipulator and supported in the series of saw-tooth serra-

tions thereof, and as the manipulator is lowered, the blooms, billets or slabs contact with the collars or projections of the table rollers and are turned on their axes as desired before entering the next pass. By reason of this arrangement the various passes of the rolls are kept in operation at all times which thereby largely increases the product and reduces the rolling expense.

Although I prefer to use a table with a plurality of lifting rollers having grooves therein formed by the collars or otherwise, I may use a stationary table forming a fixed structure having projections between the rotatable rollers forming aligned grooves.

Having thus given a general description of my invention, I will now, in order to make the matter more clear, refer to the annexed sheet of drawings, which forms part of this specification, and in which like characters refer to like parts:

Figure 1 is a top plan view of a portion of a rolling mill feed table of a special form illustrating the application of my invention; Figure 2 is a vertical transverse sectional elevation through the feed table taken on the line II—II of Figure 1; Figure 3 is a detail longitudinal sectional elevation of a portion of the feed table; Figure 4 is a detail sectional elevation through the movable joint of the actuating bar and the connecting links; Figure 5 is a detail sectional elevation through the pivoted end of the actuating bar; Figure 6 is a detail view showing one of the manipulator table rollers in side elevation with the billets turned a quarter of a revolution to the position shown in Figure 2 and shifted to the next groove in the rollers.

Referring now to the characters of reference on the drawing 1 are the longitudinal side base frames of the roller feed table upon which the table rollers 2 are rotatably mounted, 3 are the bevel gears on the ends of the shafts of the table rollers, 4 are the other bevel gears mounted on the drive shaft 5 adapted to mesh with and drive the rollers 2 by means of the bevel gears 3 mounted thereon, 6 are annular collars mounted on or forming part of the table rollers forming spaces or grooves 7, 8, 9 and 10 therebetween; 11, 12, 13 and 14 represent blooms or billets in various stages of completion and 15 are the serrated or notched lifting and lowering members of my manipulator, these being provided with notches or serrations 16, 17, 18 and 19 in

the upper surfaces thereof; 20 are spacing members secured between the lower portions of the lifting members 15 in order to maintain them in position and alignment so that 5 they will operate together in pairs; 21 are the outer portions of the spacers and 22 and 23 are openings provided in the lifting members 15 and 20 as illustrated, and adapted to receive the wedges 24, which secure the 10 lifting members 15 to the lower portion of the manipulator construction; 25 and 26 are the actuating bars of the manipulator secured by bolts 27 to the member 20, these bolts also being provided with tubular spacing washers 28 as illustrated; 29 are pivot bolts passing through the ends of the actuating bars 25 and around which they are adapted to be partially rotated, these bolts being mounted in the castings 30, which are 15 secured to the channels 33 by means of the flanges 31 and the bolts 32 passing therethrough, while 34 is a longitudinal horizontal channel upon which the channels 33 are mounted; 35 are tie bars mounted on the 20 tops of the channels 33 at the side of the casting 30, bracing and connected to the longitudinal horizontal channels 34 by the bolts 36; 37 are pivot bolts passing through the movable ends of the actuating bars 25 25 and 26, provided with washers or filler blocks 38 between these two members, and further provided with links 39 pivoted to the bolts 37, the ends of the links 39 being pivotally secured by means of the bolts 40 30 to the short rocker arms 41; 53 are longer rocker arms mounted on the rock shaft 42 provided with pivot bolts 43 near the ends of the upper legs thereof; 44 is a pitman pivotally mounted on the bolts 43 and 45; 40 46 are small crank arms mounted on the rotating shaft 47, which shaft is also provided with a gear 48 which meshes with a pinion 52 mounted on the shaft 55, which latter shaft 55 has mounted thereon a gear 45 49 which meshes with the pinion 50 on the end of the motor shaft of the motor 51; 54 are the rolls of the rolling mill provided with grooves therein as illustrated and mounted as usual in roll housings 56.

50 Having thus described my apparatus, I will now describe how it operates: The rolls 54 of the mill receive the bars, blooms, billets or slabs in the various passes thereof, which are delivered in the direction of and 55 to the feed table and are there received by the rollers 2 thereof within the grooves 7, 8, 9 and 10 formed by the collars of said rollers. After the pieces have issued from the mill and it is desired to transfer them to the next pass for further operation, the manipulator is moved upwardly and lifts each of the blooms, billets or slabs between the collars on the feed table rollers, and after this lifting operation is finished the manipulator is lowered and as this is done 60 the lower surfaces of the blooms, billets or slabs contact with the collars of the feed table rollers and the pieces are thereby turned approximately ninety degrees and laterally delivered into the next adjacent 70 groove in the feed rollers, and are thence longitudinally delivered to the next grooves in the mill by the rotation of the rollers. This process is repeated continuously and in such a way that practically all the passes 75 in the rolls may be operated at the same time, thereby increasing the product of the mill.

As illustrated in Figure 2, the blooms or billets 11, 12, 13 and 14 are resting on the 80 feed rollers in the grooves thereof as shown by the full lines. The manipulator bars 15 are then moved upwardly and these blooms or billets are lifted to the positions shown by the dotted lines, whereupon they slide 85 down the serrations of the manipulator to the right, whereupon the manipulator is lowered, and as this is done the pieces contact with the upper edges of the collars and are turned substantially ninety degrees on 90 their axes and delivered into the next grooves of the rollers in position to be delivered to the next passes of the rolling mill for further reduction. This process is continuous, so that larger blooms, billets or 95 slabs are successively delivered to the first or larger passes of the rolling mill and are reduced to their final sizes as delivered from the last pass thereof. For example, a 7 inch x 8 inch bloom may be rolled to a 100 4 inch x 4 inch billet, this 7 inch x 8 inch bloom entering the table with its 8-inch side resting on the rollers, is transferred and turned ninety degrees on its axis and edged to enter the 7-inch pass by the saw-tooth 105 manipulator member, which, as it rises, lifts the piece gradually and allows it to slide into or rest in the bottom portion of the serration, and then as the manipulator is lowered delivers it to the next groove in the 110 feed rollers, and as this is done the lower surfaces of the piece contact with the upper edges of the collars of the feed rollers, which turn the piece ninety degrees on its axis and delivers it to the next groove of the rollers and thence by rotation of the rollers to the mill, into which it is entered for further reduction.

Although I have shown and described my invention in considerable detail, I do 115 not wish to be limited to the exact and specific details thereof, as shown and described, but may use such modifications in, substitutions for, or equivalents thereof as are embraced within the scope of my invention, or as pointed out in the claims.

When my manipulator is moved upwardly it lifts the pieces from the table rollers and under certain conditions allows the pieces to slide laterally by gravity to the bottom of 130

the serrations, thus partially aiding in their lateral transfer.

Having thus described my invention, what I claim and desire to secure by Letters 5 Patent is:

1. A rolling mill feed table having a plurality of rollers with aligned grooves therein, a manipulator between said rollers provided with a corresponding series of aligned 10 serrations, and means for moving said manipulator upwardly and downwardly.

2. A rolling mill feed table having a plurality of rollers with aligned grooves therein, a manipulator provided with a corresponding series of aligned serrations and means for moving said manipulator relatively to the said rollers in a curve.

3. A rolling mill feed table having a plurality of rollers with a series of approximately 20 rectangular grooves therein, a manipulator mounted between said rollers provided with a corresponding series of saw-tooth serrations in its upper surface, the lower portions of said serrations being inclined 25 to the axes of said rollers, and means for moving said manipulator in a curve relatively to said rollers.

4. A rolling mill feed table having a plurality of rollers provided with a series of 30 aligned grooves of successively decreasing sizes formed therein, a manipulator arranged between said rollers provided with a corresponding series of aligned serrations of decreasing sizes and means for moving 35 said manipulator above and below the upper surfaces of said rollers.

5. A rolling mill appliance comprising a feed table provided with a plurality of longitudinal grooves therein adapted to register 40 with corresponding grooves in the rolls, a manipulator provided with a corresponding plurality of serrations in its upper surfaces and adapted to be moved upwardly and downwardly, thereby laterally transferring pieces from one groove to the next 45 while partially rotating said pieces.

6. A rolling mill appliance comprising a stationary feed table provided with a plurality of rotatable rollers having aligned 50 grooves therein, in combination with a manipulator mounted therebetween and having a corresponding series of serrations, and means for moving said manipulator upwardly and downwardly, whereby the pieces 55 in the process of handling are transferred laterally from groove to groove and partially rotated on their axes.

7. A rolling mill appliance comprising a stationary feed table provided with a plurality of rotatable rollers mounted thereon, said rollers being provided with a plurality 60 of aligned grooves therein, in combination with a manipulator mounted between said rollers and having a corresponding series 65 of serrations in the upper surfaces there-

of, and means for moving said manipulator upwardly and downwardly, whereby pieces in process of rolling are transferred laterally from groove to groove and partially rotated on their axes.

8. A rolling mill appliance comprising a stationary feed table provided with a plurality of rotatable rollers mounted thereon and means for rotating same in either direction, said rollers each being provided with a plurality of grooves or collars forming 70 grooves therein adapted to register with each other, in combination with a manipulator mounted between said rollers and having a corresponding series of serrations in 75 its upper surface, said manipulator being pivotally mounted, and means for rocking same upwardly or downwardly, whereby pieces in process of rolling are transferred laterally from groove to groove and partially rotated on their axes.

9. A rolling mill appliance comprising a stationary feed table provided with a plurality of rotatable rollers mounted thereon and means for rotating same in either direction, said rollers being provided with a plurality of grooves adapted to register with each other, in combination with a manipulator mounted between said rollers having 90 a plurality of saw-tooth serrations in the upper surfaces, said serrations being adjacent to each of the grooves aforesaid, and means for raising said manipulator, whereby pieces in process of rolling are lifted from one groove and for lowering the same 95 100 whereby the lower surfaces of said pieces contact with the upper portions or boundaries of the grooves in the rollers, whereupon a further lowering of the manipulator results in turning the pieces approximately 105 ninety degrees on their axes and delivers them to the next grooves in the rollers.

10. A rolling mill appliance comprising a stationary feed table provided with a plurality of rollers, each having a number of 110 collars thereon forming a plurality of aligned grooves in said rollers, a plurality of manipulators mounted between said rollers and provided with a series of saw-tooth serrations in their upper surfaces corresponding 115 to the grooves in said rollers, said manipulators being mounted upon actuating bars of considerable length pivoted near their ends, means for lifting and lowering the other ends of said bars and manipulators, whereby pieces are lifted from one groove of the rollers and deposited in the next groove while being turned ninety degrees on their axes by contact with the collars as they are lowered on said rollers.

11. A rolling mill appliance comprising a stationary feed table provided with a plurality of rollers, each having a number of collars thereon forming a plurality of aligned grooves in said rollers, a plurality 120 125 130 of serrations in the upper surfaces there-

of manipulators mounted between said rollers and provided with a series of saw-tooth serrations in their upper surfaces corresponding to the grooves in said rollers, said manipulators being mounted upon actuating bars of considerable length pivoted near their ends, means for lifting and lowering the other ends of said bars and manipulators, whereby pieces are lifted from

one groove of the rollers, slid laterally and downwardly in the serrations, and deposited in the next groove while being turned ninety degrees on their axes by contact with the collars as they are lowered on said rollers.

In witness whereof I hereunto affix my signature.

TOM WILSON
